UNITED STATES PATENT OFFICE

JAMES J. HARTLEY, OF SCHENECTADY, NEW YORK, ASSIGNOR TO GENERAL ELECTRIC COMPANY, A CORPORATION OF NEW YORK.

INCANDESCENT-LAMP SOCKET.

No. 831,480.

Specification of Letters Patent.

Patented Sept. 18, 1906.

Application filed April 27, 1905. Serial No. 257,595.

To all whom it may concern:

Be it known that I, JAMES J. HARTLEY, a citizen of the United States, residing at Schenectady, county of Schenectady, State of New York, have invented certain new and useful Improvements in Incandescent-Lamp Sockets, of which the following is a specification.

The present invention relates to incandescent electric lighting, and more particularly to lamp-sockets of the Edison type in which a screw-shell contact is provided for the reception of the terminal end of a lamp.

The object of my invention is to provide a device of this character having a single-piece base with a switch-key mounted thereon and operative in a direction transverse to the axis of the base, so that variations in the length of the base and the relative position of the screw-shell to the switch mechanism will not affect the proper action of the switch.

In the accompanying drawings, forming a part of this specification, Figure 1 is a plan of the base and switch mechanism of a socket embodying one form of my invention. Fig. 2 is a vertical section of the socket without the inclosing shell, taken on line 2 2 of Fig. 1; and Fig. 3 is a side elevation of the same with a part shown broken away.

The base 1, which is of porcelain or other moldable insulating material, is made cylindrical at the lower part and frusto-conical at the upper part. In the upper end of the base is formed a central rectangular recess 2 with openings 3 4 leading therefrom at right angles to each other, and in the side of the base opposite to opening 3 is a recess 5, separated from the central recess by a barrier 6. Adjacent the recess 5 and the opening 3 are formed semicircular grooves 7, and in the lower end of the base are formed a countersunk screw-hole 8 and a channel 9 with screw-holes extending upwardly from each end.

The switch mechanism consists of a key-shaft 10, provided with side lugs 11 and journaled in a U-shaped frame 12. At the inner end of the shaft is journaled a switch-block 13 with a transverse gain 14, in which the lugs 11 at the inner end of the shaft may move with considerable lost motion before engaging the opposite sides of the gain. The U-shaped frame 12 is disposed transversely to the axis of the base 1 and is of a size to

closely engage three sides of the rectangular recess 2 and is held in place by a screw 15, extending through the base and engaging a threaded lug 16, bent up from the lower edge of the frame. A bent spring 17 is secured to the side of the frame parallel to the shaft 10 and extends at its free end into position to bear upon the edge of the switch-block 13 in such a manner as to normally press the latter outwardly in a direction transverse to the axis of the base. The bearing in the frame 12 for the inner end of the shaft is made considerably larger than the shaft to permit of a bodily movement of that end of the shaft with the switch-block 13. The operating end of the shaft 10 extends through opening 4, and in the opening 3 is arranged a U-shaped contact 18, seated in a shallow recess in the bottom of the opening and secured in place by a screw 19. The outer end of the contact 18 is provided with a binding-screw 20, and the inner end lies between the walls of the opening 3 in position to be engaged by the switch-block 13.

In the recess 5 is secured the center contact member 21, consisting of a strip of spring metal bent to the desired shape, provided with a binding-screw 22 and held in place by a screw 23.

The screw-shell contact 24 is of the usual construction and is held in place on the upper end of the base by two screws 25, which extend through the base when one is engaged by a nut while the other is engaged by a flat metal strip 26, lying in the channel 9, which extends lengthwise thereof and engages at its opposite end with screw 15, whereby the switch-frame 12 is electrically connected to the screw-shell 24.

I do not desire to restrict myself to the particular form or construction of parts herein described and shown, since it is apparent that they may be changed and modified without departing from my invention.

What I claim as new, and desire to secure by Letters Patent of the United States, is—

1. In a lamp-socket, the combination of a one-piece base, a screw-shell contact mounted upon one end of said base, a switch member, a U-shaped switch-frame mounted on said base transversely to its axis and electrically connected to said shell, and a stationary contact secured to said base in position to be engaged by said switch member.

2. In a lamp-socket, the combination of a one-piece base provided with a central rectangular recess having openings from two sides thereof, a switch member having its shaft extending through one of said openings into said recess, a U-shaped switch-frame secured in said recess transversely to the axis of the base, and a stationary contact arranged in the other opening in position to be engaged by said switch member.
3. In a lamp-socket, the combination of a one-piece base having a side recess and a rectangular center recess separated from the side recess and connected to two side openings at right angles to each other, a screw-shell contact secured to the upper end of said base, a center contact secured in the side recess, a switch member having its shaft arranged in one of said openings, a U-shaped switch-frame disposed at right angles to the axis of said base and electrically connected to

said screw-shell, and a stationary contact secured in the other opening in said base.

4. In a lamp-socket, the combination of a one-piece base having a central rectangular recess with two openings leading therefrom at right angles to each other, a switch member having its shaft entering said recess through one of said openings, a U-shaped frame arranged in said recess in engagement with the walls on three sides thereof and provided with a contact-spring normally acting to force the switch transversely to the axis of the base, and a stationary contact arranged in the other opening in position to be engaged by said switch member.

In witness whereof I have hereunto set my hand this 25th day of April, 1905.

JAMES J. HARTLEY.
